Primary Examiner—Ruth McInroy*Attorney, Agent, or Firm*—Wolf, Greenfield & Sacks, P.C.**[57] CLAIM**

The ornamental design for an antenna cover, as shown and described.

DESCRIPTION

FIG. 1 is a front elevational view of an antenna cover showing my new design, the rear view being identical; FIG. 2 is a right side elevational view thereof, the left side being identical;

FIG. 3 is a top plan view thereof;

FIG. 4 is a bottom, elevation view thereof with the antenna base; and,

FIG. 5 is a bottom, elevation view thereof without the antenna base.

The details shown in broken lines in FIGS. 1, 2 and 4 are for illustrative purposes only and form no part of the claimed design.
